(57) **CLAIM**

The ornamental design for an exercise board, as shown and
described.

DESCRIPTION

FIG. 1 is an upper front right perspective view of an exercise
board;

FIG. 2 is another upper front right perspective view of FIG.
1;

FIG. 3 is an upper front left perspective view of FIG. 1;

FIG. 4 is a rear right perspective view of FIG. 1;

FIG. 5 is a rear left perspective view of FIG. 1;

FIG. 6 is another rear right perspective view of FIG. 1;

FIG. 7 is a left side perspective view of FIG. 1;

FIG. 8 is an exploded perspective view of FIG. 1;

FIG. 9 is an exploded right side view of FIG. 8;

FIG. 10 is an exploded rear side view of FIG. 8;

FIG. 11 is a front perspective view of the top piece of FIG.
1-10;

FIG. 12 is a rear perspective view of the top piece of FIG.
11;

FIG. 13 is a bottom end perspective view of the top piece of
FIG. 11;

FIG. 14 is an upper front perspective view of the rear vertical
support piece of FIG. 1-10;

FIG. 15 is an upper front right perspective view of the rear
vertical support piece of FIG. 14;

FIG. 16 is a left side view of the rear vertical support piece
of FIG. 14;

FIG. 17 is a rear perspective view of the rear vertical support
piece of FIG. 14;

FIG. 18 is a bottom end perspective view of the rear vertical
support piece of FIG. 14;

FIG. 19 is a right side perspective view of the right support
piece of FIG. 1-10;

FIG. 20 is an upper right perspective view of the right
support piece of FIG. 19;

FIG. 21 is a top side perspective view of the right support
piece of FIG. 19;

(Continued)

FIG. 22 is an upper front left side perspective view of the right support piece of FIG. 19;
 FIG. 23 is a left side perspective view of the left support piece of FIG. 1-10;
 FIG. 24 is an upper front left side perspective view of the left support piece of FIG. 23;
 FIG. 25 is a top side perspective view of the left support piece of FIG. 23; and,
 FIG. 26 is an upper right side perspective view of the left support piece of FIG. 23.
